UNITED STATES PATENT OFFICE.

PIERRE JOSÉ BOUCHER, OF CHELSEA, LONDON, ENGLAND.

COVER OR STOPPER FOR JARS, POTS, BOTTLES, AND OTHER RECEPTACLES.

1,258,390.

Specification of Letters Patent.

Patented Mar. 5, 1918.

Application filed October 21, 1914. Serial No. 867,888.

To all whom it may concern:

Be it known that I, PIERRE JOSÉ BOUCHER, a subject of the King of Great Britain and Ireland, residing at 132 Lots road, Chelsea, 5 London, England, have invented new and useful Improvements in Covers or Stoppers for Jars, Pots, Bottles, and other Receptacles, of which the following is a specification.

10 This invention relates to covers or stoppers for jars, pots, bottles and other receptacles and has for its object the production in thin sheet metal or equivalent material of covers of the same form as those usually 15 made of glass, earthenware, or other solid material. Not only are the covers made according to this present invention much lighter in weight but they are cheaper to manufacture and they possess the further 20 advantage of being applicable to receptacles the mouth of which is irregular in form.

Referring to the drawings which form part of this specification,

Figure 1 shows in perspective the upper 25 domed part of the stopper, with a downwardly extending flange formed around its edge.

Fig. 2 shows in perspective the lower hat shaped part of the stopper.

30 Fig. 3 shows in perspective the two parts shown in Figs. 1 and 2 assembled and with the flange of the upper part closed down.

Fig. 4 shows the stopper in diametrical section.

35 Fig. 5 shows in perspective, the bottle neck, stopper and retaining band disassociated.

Fig. 6 shows in perspective the bottle 40 closed and sealed with my improved stopper.

To carry the invention into effect I take a disk of metal *a* and by stamping pressure form a downwardly extending flange *b* around its edge and raise the central portion *c* into a domed formation thereby producing the stamping illustrated in Fig. 1. Into the space inclosed by the downwardly extending flange *b* I dispose a stamping of hat formation as illustrated in Fig. 2 which 45 has a flange *d* of considerable width and a central substantially cylindrical portion *e* of smaller diameter; the flange *b* being beaded down upon the flange *d* so as to tightly hold the two parts together and produce a

stopper substantially as illustrated in Fig. 3, 55 having a flange with a certain amount of flexibility relative to said stopper.

In practice I prefer to raise the upper part of the stopper as shown in the section illustrated in Fig. 4 as thereby less lodgment for dust and dirt is provided.

A cover or stopper formed as hereinbefore described has a plug portion *e* adapted to fit the neck *f* of the receptacle and a laterally extending flexible flanged portion *g* 65 adapted to form a supporting surface for a cork, rubber or other closing washer and cause it to conform to the upper surface of the neck of the receptacle.

It will be seen that owing to the flexible 70 nature of the laterally extending flange *g* a hermetical joint can be readily made on receptacles having irregular necks without employing excessive pressure owing to the narrowness of the beaded over portion of the 75 flange *b* in contact with the closing washer.

In order to hold the stopper in position in the neck *f* of the receptacle a flanged band *h* of usual construction is used, the said band *h* being placed about the stopper and neck *f* 80 of the receptacle and then fixed in position by having its lower edge turned under the rim of the said neck, the stopper being maintained in position with sufficient pressure to cause hermetical sealing.

85

I claim:—

A closure for jars or the like comprising a stopper, a horizontal annular flange formed on said stopper and corresponding in width to the width of the top wall of the 90 neck of a receptacle to which it is applied, said flange being formed of flexible material and arranged to rest on the top wall of the neck of a receptacle when said stopper is in position, a ridge formed on the underside 95 of said flange at its marginal edge, a washer interposed between said flange and the top wall of the neck of the receptacle, and means for clamping said flange in engagement with the neck of a receptacle, in a direction 100 parallel to the axis of the neck.

In testimony whereof I have signed my name to this specification in the presence of two subscribing witnesses.

PIERRE JOSÉ BOUCHER.
